UNITED STATES PATENT OFFICE.

EDWARD J. WESSELS, OF WESTFIELD, AND GEORGE S. LEE, OF HAWTHORNE, NEW JERSEY, ASSIGNORS TO THE STANDARD AIR BRAKE COMPANY, OF NEW YORK, N. Y.

AIR-BRAKE.

SPECIFICATION forming part of Letters Patent No. 548,335, dated October 22, 1895.

Application filed March 8, 1895. Serial No. 541,065. (No model.)

To all whom it may concern:

Be it known that we, EDWARD J. WESSELS, a subject of the Queen of Great Britain, residing at Westfield, county of Union, and 5 GEORGE S. LEE, a citizen of the United States, residing at Hawthorne, county of Passaic, State of New Jersey, have invented certain new and useful Improvements in Air-Brakes, of which the following is a specification.

10 Our invention relates to certain improvements in brakes which are intended to be controlled by a motorman, brakeman, or driver on a car-platform.

A form of air-brake for individual cars has 15 been used in which a pump operated by the rotation of the car-axle supplies air to reservoirs whence it is led to the brake-cylinder of the brake. The flow of the air to the reservoir and the brake-cylinder has been governed by a hand-lever and valve on the platform, and the air-pressure had to act through 20 pipes of considerable length in order to pass by way of said valve. A loss of time and of pressure resulted from this. The form of 25 pump employed is also imperfect. Operating a pump under a car involves the subjection of the apparatus to very severe test, because of the jarring motion and the dust and dirt, and the pumps heretofore employed have not 30 been entirely equal to coping with these difficulties.

Our improvement, therefore, relates to an 35 air-brake system for individual cars which possesses greater simplicity as to the circulation part of the system, greater strength and durability of the pump and other parts of the system, and has certain other advantages which we will refer to more fully hereinafter in describing the details of our improved apparatus.

40 Referring to the accompanying drawings, which form a part of this specification, Figure I is an under side view of a car-body and car wheels and axles, showing our improvements applied thereto. Fig. II is a partly-sectioned side view of our improved flexible coupling. Fig. III is a side elevation of an eight-wheel car to which our invention is applied, partly broken away to show the air-reservoir and

the connection therefrom to the car-platform. 50 Fig. IV is a top view of the gage and quadrant. Fig. V is a side elevation thereof. Fig. VI is a sectional elevation of the valve, the operating-chain not being shown. Fig. VII is a top view thereof, showing the operating- 55 chain. Fig. VIII is a horizontal sectional view of the valve-casing, the plane of section being indicated by dotted line VIII VIII, Fig. VI. Fig. IX is a top view of the valve. Figs. X and XI are views of the corresponding meeting faces of the two parts of said valve. Fig. XII is a vertical sectional view of one form of our pump with its casing. Fig. XIII is a horizontal sectional view of the same. Figs. XIV and XV are views similar to Figs. XII and 60 XIII, illustrating another form thereof. Figs. XVI and XVII are similar views illustrating another modification. Figs. XVIII and XIX are similar views illustrating still another form. 70

Referring to Fig. I, 1 is a car-body, and 2 are the axles of the car. 3 is an air-pump, hung at one end from one of the axles 2 by means of its casing 4, which is boxed on said axle, and at the other end by link 5 (see Fig. 75 XIV) from the car-body. 6 is the air-reservoir, located under the car-body, as in Fig. I, or within the same, as in Fig. III, and receiving air from pump 3 by pipe 7. A pipe 8 leads from the reservoir 6 to the casing 9 of 80 the controlling-valve. Another pipe 10 leads from said casing to the brake-cylinder 11, which has the piston 12 for actuating the brake-beams. (Not shown.) Another pipe 13 leads from the valve-casing into an exhaust- 85 cylinder 14, which has the wire-netting or other perforated ends 15, and has a pipe 16 communicating with the inlet of pump 3. The structure of the valve is shown in Figs. 90 VI to XI. Within the casing 9 is arranged the valve 17, having a stem 18, on which are fixed the two sprocket or other wheels 19 of operating chains or cables 20. The body of the valve 17 is frusto-conical, as shown, to engage the correspondingly-shaped walls of 95 the casing 9, so as to allow adjustment of the valve to take up wear. The upward taper of the valve and its seat also precludes the pos-

sibility of wedging of the valve by reason of the jarring action of the car. The body of the valve is made in two parts, held together in any desired way, and the parts have on their 5 adjacent faces the grooves 17^a, (shown in Figs. X and XI,) which when the two parts are placed and fixed rigidly together form the passage shown in dotted lines in Fig. IX. A pin 21 on the casing engages a slot 22 on the 10 upper half of the valve-body 17 to limit the motion of the valve.

The operating-chains 20 are connected by rods 23 with chains 24 on sprocket-wheels 25 at the base of staffs 26 on the car-platform, 15 having at their upper ends hand-levers 27, moving over quadrants 28. Sunk into the quadrant 28, in position to be constantly observed by the gripman or motorman, is a gage 29, which has connection by a small pipe 30 20 directly with the air-reservoir 6.

By operating the hand-lever 27 the valve 17 can be turned in its casing, thus causing the reservoir 6 to supply air to the brake-cylinder 11 or causing the said brake-cylinder to 25 exhaust through the valve into the exhaust-cylinder 14. The purpose of the exhaust-cylinder is to deaden the noise of the escaping air, at the same time supplying an already-strained body of air to the pump 3. The 30 pump 3 is constantly in action while the car is moving; but by reason of the regulating apparatus 31, well known in this class of apparatus, it only pumps air into the cylinder 6 up to a certain pressure and then runs 35 freely. The form of pipe connection shown is adapted to secure the flow of air through the valve with the least possible loss of time and pressure.

A great deal of trouble has been caused in 40 these structures heretofore by the shaking apart and loosening of the couplings, owing to the jar of the car. To obviate this we provide in each pipe a flexible coupling such as shown in Fig. II—that is to say, each of 45 the pipes 7 8 10 13 16 is at some point coupled by an armored rubber tube 32, securely fastened in place, which not only allows of considerable latitude of adjustment of the pipes to place, but gives such a resili- 50 ent action to the pipes that they cannot jar loose from their connections.

The pump and the driving parts thereof are all thoroughly protected from the dust. The cylinder 33 thereof is rigidly united with 55 the casing 34. In fact, the two form a single casing for the moving parts of the pump, and the part 34 of the casing is boxed on the axle 2, as already described.

The casing may be put together in any pre- 60 ferred way. We have shown in the drawings several different ways of accomplishing this. In Fig. XII the piston 35 of the pump is shown driven by a pitman 36, strap 37, and eccentric 38 from the axle 2, all of which parts are, as

will be seen, thoroughly protected by casing 65 33 34.

In Figs. XIV and XV, instead of an eccentric being arranged on the axle 2, we provide thereupon a pinion 39, which drives a gear 40, mounted on a pin 41 on the casing 34. 70 The gear 40 carries a wrist-pin 42, which operates a pitman 36, connected to the piston 35.

In Figs. XVI and XVII the pinion 39 drives a gear 40, which has instead of the wrist-pin 42 a cam-groove 43, in which travels a pin 44 75 on rod 45, which is guided to a right line by slot 46 and the pivot-pin 47 of gear 40.

A receptacle 48 for oil, provided with a dripping-aperture 49 and, if desired, a wick 50, may be provided in the casing 34 in such position as to supply oil to the contact faces of the pinion and gear 39 40. 80

Another form of the pump is shown in Figs. XVIII and XIX, in which an eccentric groove 51 is formed in a disk 52, placed directly upon the car-axle 2. In the groove 51 travels the pin 44 on the piston-rod 45, and the yoke 53 of the piston-rod is here enlarged sufficiently to embrace the axle 2, which therefore guides the rod to a right line. 90

The disk 52 is provided with a hole 54 and the casing 34 with a door 55, to allow the pin 45 and the antifriction-roller 56 thereon to be inserted and replaced when necessary.

Having thus described our invention, the 95 following is what we claim as new therein and desire to secure by Letters Patent:

1. The combination of the air reservoir, the valve and valve casing, the brake cylinder, the air pump and the exhaust cylinder 14 100 connected to said valve casing and to the air pump cylinder and having means for admitting atmospheric air and for straining the same substantially as set forth.

2. The combination of the air reservoir, the 105 controlling staffs, the quadrant, having a seat for a gage, the controlling lever and the pressure gage fixed in said quadrant and having an air pipe connected with said reservoir, substantially as set forth. 110

3. The combination of the casing 33, 34, the piston 35, the car axle 2 whereon the casing 34 is boxed, the piston rod 45 having the yoke 53 and pin 44 and the eccentric 52 having groove 51 substantially as set forth. 115

4. The combination of the casing 33, 34, the part 34 having the door 55, the eccentric 52 having groove 51 and hole 54, the part 33 of the casing having piston 35 and the piston rod 45 having yoke 53 and pin 44 all arranged 120 and adapted to operate, substantially as and for the purposes set forth.

EDWARD J. WESSELS.
GEORGE S. LEE.
